ANGLE MEASURING GAUGE

Arthur H. Schimmelman, 3093 Molokai Place,
Costa Mesa, Calif.

Filed Dec. 31, 1962, Ser. No. 73,018

Term of patent 14 years

(Cl. D52—6)

FIG. 1 is a perspective view of the angle measuring gauge shown in a partially opened position;

FIG. 2 is a front elevational view of the gauge of FIG. 1;

FIG. 3 is a view of the left hand end of FIG. 1;

FIG. 4 is a rear elevation of FIG. 1;

FIG. 5 is a right hand end view of FIG. 1;

FIG. 6 is a top plan view of the device of FIG. 1;

FIG. 7 is a bottom view of FIG. 1.

I claim:

The ornamental design for an angle measuring gauge, substantially as shown.
